UNITED STATES PATENT OFFICE.

SAMUEL H. BOYLAN, OF JOPLIN, MISSOURI.

ATTACHMENT FOR ORE-CONCENTRATING JIGS.

Application filed January 19, 1923. Serial No. 613,752.

To all whom it may concern:

Be it known that I, SAMUEL H. BOYLAN, a citizen of the United States, residing at Joplin, in the county of Jasper and State of Missouri, have invented certain new and useful Improvements in Attachments for Ore-Concentrating Jigs, of which the following is a specification.

This invention relates to attachments for ore concentrating jigs, and more particularly to automatic draw-off mechanism therefor.

The invention relates to jigs used in separating lead and zinc ores from rock, and other waste material after the mine run has been crushed. These jigs consist of a casing having a screen over which the ore is passed, and containing a body of water which is agitated to settle the ore.

Heretofore, it has been impossible to efficiently withdraw the ore from the screen. The best jiggling method is to maintain a constant bed of clean ore adjacent the top of the grate and to draw off the ore as it accumulates above a certain depth, the ore being withdrawn from the bottom without disturbing the surface of the bedding ore.

In the present invention, I provide a jig of the usual construction, consisting of a casing having a grate, and I further employ an automatic draw-off consisting of a trough having its upper surface in alignment with the grate, and forming a portion thereof. This trough extends through an opening in the side of the casing, and a receptacle is pivotally mounted therein. The ore collecting on the grate passes into this receptacle, which is normally closed at its outer end by an automatic valve. When the weight of the material within the receptacle is sufficient to move the receptacle, the valve is opened and a portion of the material discharged. As soon as the weight decreases sufficiently by the discharge of material, the receptacle returns to its normal position.

By means of this construction, an automatic draw-off is obtained which will maintain a constant depth of ore on the grate, and which discharges from the bottom.

In the accompanying drawings, I have shown one embodiment of the invention. In this showing:

Figure 1 is a front elevation of a jig comprising a plurality of independent cells,

Figure 2 is a transverse sectional view on line 2—2 of Figure 1,

Figure 3 is a plan view,

Figure 4 is a longitudinal vertical sectional view on line 4—4 of Figure 3, and, 60

Figure 5 is a detail sectional view of the trough and receptacle.

Referring to the drawings, the reference numeral 1 designates generally a casing forming the jig. In this instance, I have 65 shown a jig consisting of a plurality of separate cells 2, 3, and 4, separated from each other by transverse partitions 5. As shown, the partition walls are of different height, the upper edge of each wall being lower 70 than the upper edge of the adjacent wall to the left. The front wall of the trough is likewise provided with vertical portions 6, separating the upper edge of the adjacent cells, whereby the wall is gradually lowered 75 toward the right.

Each of the cells is provided with a guide frame 7 having a plunger 8 operating therein. The plunger is connected to a rod 9, having an eccentric 10 on its upper end. 80 This eccentric surrounds a shaft 11, which extends the entire length of the jig and is mounted in suitable bearings 12. The shaft may be driven in any suitable manner, as by a belt (not shown) passing over a pulley 13 on the shaft. The section of the cell not occupied by the guide frame is provided with a grate or screen 14. As shown, the grate is provided with the usual rectangular openings 15 for the passage of 90 water. The grate is supported on suitable bars 17, secured to the front wall of the casing and to the guide frame. Intermediate the partition walls, the grate is provided with an open portion adapted to receive the upper edge of a trough 18. As shown, the cross-sectional area of the trough is equal to the size of the opening in the grate and it is adapted to completely fill this 95 opening. The upper edge of the trough is provided with a flange 19, adapted to rest upon the grate and the supporting bars 17. The bottom of the trough is provided with an inclined wall 20, and the front of the receptacle is provided with an opening 21, ex- 100

tending through an opening in the front of the casing. A receptacle 22 substantially similar in shape to the trough is arranged therein and is pivotally mounted on pins 23 arranged at the rear and passing through 110

the walls of the trough. Suitable packing 24' may be arranged at the top between the wall of the receptacle and the wall of the trough. The receptacle is also provided with an inclined lower wall 24, terminating in a spout 25. A bracket 26 is mounted on the front wall of the casing and this bracket is provided with a pair of depending ears 27 adapted to pivotally support an arm 28. A 10 weight 29 is secured to the outer end of this arm and a link 30 is secured to the inner end of the arm. This link is connected to a pair of ears 31, arranged on the spout 25. A second link 32 is arranged intermediate 15 the ends of the arm 28 and the lower end of this link is connected to a bracket 33, arranged on a valve 34, adapted to close the lower end of the spout. A bracket is provided with an arm 35, extending over the 20 spout, pivotally supported in a pair of ears 36, arranged thereon.

In operation, the ore is fed over the grate in the usual manner, and is agitated by the reciprocation of the piston or plunger in 25 the guide frame which causes the water to flow upwardly through the grate. By providing a plurality of cells arranged at different elevations, with the grates similarly arranged as shown in Figure 4 of the drawings, the material may be fed to the jig at 30 one end and permitted to flow over the entire length. The ore concentrated in each cell settles on the grate in the usual manner, and the heavier material passes through 35 the open, upper end of the receptacle 18 into the trough 22. When the weight of the material in the receptacle 22 becomes sufficient to overcome the weight 29, the trough automatically lowers and thus opens the valve 40 34, permitting discharge of a portion of the contents. The material will discharge from the receptacle until the weight of the contained material becomes insufficient to retain the receptacle in lowered position when 45 the weight 29 will return it to normal position and close the valve 34. This operation will be repeated as long as the material is fed to the receptacle and it will thus be seen that the ore is removed from the bottom of 50 the grate and a substantially constant level of material maintained on the grate at all times.

It is to be understood that the form of my invention herewith shown and described is to be taken as a preferred example of the 55 same, and that various changes in the shape, size, and arrangement of parts may be resorted to without departing from the spirit of the invention or the scope of the subjoined claims.

Having thus described my invention, I claim:

1. An attachment for jigs comprising a trough extending downwardly from the grate of the jig, said trough being provided with an inclined bottom, a receptacle mounted in said trough and shaped to conform substantially to the shape of the trough, the ore on said grate being adapted to settle in said trough, and means controlled by the 70 weight of the ore to remove it from said receptacle.

2. An attachment for jigs comprising a trough extending downwardly from the grate of the jig, said trough being provided with an inclined bottom extending through the side of the jig, a receptacle pivotally mounted therein and provided with a spout projecting from the jig, a valve adapted to close said spout when in one position, said receptacle being adapted to lower to open said spout when the weight of the ore therein exceeds a predetermined limit, and means for returning said receptacle to normal position.

3. An attachment for jigs comprising a trough extending downwardly from the grate of the jig, said trough being provided with an inclined bottom extending through the side of the jig, a receptacle pivotally mounted therein and provided with a spout projecting from the jig, a valve adapted to close said spout when in one position, said receptacle being adapted to lower to open said spout when the weight of the ore therein exceeds a predetermined limit, and a weight connected to said receptacle to return it to normal position.

In testimony whereof, I affix my signature in presence of a witness.

SAMUEL H. BOYLAN.

Witness:

H. J. KRUGG.
